[57] **ABSTRACT**

Nitro derivatives having antimicrobial activity comprising compounds having the formula:

wherein R₁ represents a member selected from the group consisting of hydrogen, halogen, furyl and phenyl substituents; R₂ represents a member selected from the group consisting of hydrogen, an alkyl having from about one to about four carbon atoms and phenyl; R₃ represents a member of the group consisting of phenyl and A-(X)_n, A-(Y)_n, and A-(Z)_n in which A represents an alkyl radical having from about one to about six carbon atoms; X represents a member selected from the group consisting of hydrogen, hydroxyl, furyl, alkyl-sulfonyloxy having an alkyl group of from about one to about four carbon atoms and alkanoyl having an alkyl group of from about one to about three carbon atoms; Y represents a member selected from the group consisting of an arylsulfonyloxy radical, an alkyl-sulfonyloxy radical having from about one to about four carbon atoms, an aroyloxy radical, an alkoxy carbonyloxy radical having an alkyl group of from about one to about four carbon atoms and a carboxy alkanoyloxy radical having from about three to about six carbon atoms and Z represents a member selected from the group consisting of hydrogen and hydroxy, n is an integer of from about 1 to about 3, and m is an integer of from about 0 to about 1.

32 Claims, No Drawings

wherein R_4 represents a halogen, furyl or phenyl substituent; R_5 represents a phenyl group or a grouping of the formula $A - (X)_n$, in which A represents an alkyl radical having from about one to about six carbon atoms, X represents a member selected from the class consisting of hydrogen, hydroxyl, furyl, alkylsulfonyloxy having an alkyl group of from about one to about four carbon atoms and alkanoyl having an alkyl group of from about one to about three carbon atoms and n represents an integer of from about 1 to about 3; R_6 represents a radical such as $A - (Z)_n$, in which A represents an alkyl radical having from about one to about six carbon atoms, Z represents a member selected from the group consisting of hydrogen, hydroxyl, and n is as defined above; R_7 represents a member selected from the group consisting of hydrogen and an alkyl having from about one to about four carbon atoms; and R_8 represents a substituent of the class $A - (Y)_n$, wherein A represents an alkyl radical having from about one to about six carbon atoms and Y represents a member selected from the group consisting of an arylsulfonyloxy radical, an alkylsulfonyloxy radical having from about one to about four carbon atoms, and aroyloxy radical, and alkoxy carbonyloxy radical having an alkyl group of from about one to about four carbon atoms and a carboxyalkanoxy radical having from about three to about six carbon atoms; and m represents an integer of from about 0 to about 1.

The compounds represented by formula (I), noted above, may be prepared by reacting a carbonyl derivative having the formula:

wherein R_4 is as previously defined with an N-substituted hydroxyl amine compound having the formula:

wherein R_8 is as defined above.

A dehydrocondensation reaction follows and a 5-nitro-2-furylvinyl nitronate derivative having the formula (I) is obtained in good yields.

The reaction may be carried on at room temperature or in the alternative by heating the reaction mixture to an elevated temperature in the range of from about 20° to about 100° C. One may employ any one of numerous solvents, however, preferred for use in connection with the preparation of compound (I) are water, methanol, ethanol, dioxane, tetrahydrofuran dimethylsulfoxide, and dimethyl formamide. It is noted that a catalytic amount of acetic acid may be added to the reaction system so as to create a weakly acidic condition. Such an acidic condition results in the acceleration of the condensation reaction, however, the use of the catalytic material is not required so as to produce the desired compounds.

It is also noted that one may react a free hydroxyl amine or the salt thereof in the same manner so as to obtain similar results. The salt, however, should be employed in combination with enough base so as to free the hydroxyl amine from said salt. Preferably, one employs inorganic bases such as sodium hydroxide, potassium carbonate and sodium bicarbonate or organic bases such as sodium acetate, pyridine, triethylene and the like or mixtures thereof.

The subject compounds may be further reacted when R_5 represents an alkyl group substituted by one to three hydroxyl groups with alkylsulfonic acid having from about one to four carbon atoms in alkyl group or an alkanoyl acid having from about one to about three carbon atoms in the alkyl group or a

reactive derivative thereof so as to form the particular derivative of the subject compounds described. This reaction may be carried out either in the presence of or the absence of an appropriate solvent so as to form the specific derivative desired.

Compounds having the formula (II) may be prepared by reacting a compound which may be represented by the formula:

10

(VI)

15 with an N-substituted hydroxyl amine represented by the formula:

20

wherein R_8 is defined as above. According to this process, a dehydrocondensation reaction is readily performed by mixing the compounds of formulas (VI) and (VII) in a suitable solvent therefor so as to obtain the desired 5-nitro-2-furylvinyl nitronate.

25 The solvent system, reaction conditions, catalysts, and choice of free hydroxyl amine or salt are as noted in the preparation of the compounds having formula (I). That is to say, that one may react the individual compounds, either at room temperature or at an elevated temperature of from about 20° to about 100° C in a solvent which may be any one of a wide variety suitable for such a reaction. Preferred, however, are water, methanol, ethanol, dioxane tetrahydrofuran, dimethylsulfoxide, dimethylformamide and the like or mixtures thereof. Furthermore, the catalysts may be acetic acid which though it accelerates the reaction is not necessary to the completion thereof.

30 The compounds represented by formula (III) above may be prepared by reacting a compound having the formula:

40

45

wherein R_7 is as previously defined and A' is an alkyl radical having from about one to about six carbon atoms substituted with from about one to about three hydroxyl groups and m is as defined above, with an arylsulfonic acid, an alkyl sulfonic acid having from about one to about four carbon atoms in an alkyl group, an arylcarboxylic acid, an aliphatic dicarboxylic acid having from about three to six carbon atoms or a functional derivative of any one of the above acids, or an alkoxy carbonyl halide having from about one to about four carbon atoms in an alkyl group. In this process, the subject nitrofuryl nitronates of formula (III) can be obtained in high yield by reaction of the above compounds with an acid or a reactant derivative thereof either in the presence or absence of a solvent. It is also noted that one may optionally employ an accelerator (catalyst) depending upon the particular compounds involved. It is to be noted, however, that such an accelerator is not necessarily required to complete the reaction. This reaction may be successfully performed at room temperature but the cooling or heating of the reaction mixture may be effected according to the specific conditions of the particular reaction. Preferable acids or reactive derivatives for use in the esterification of the compounds of formula (VIII) are organic acids such as benzoic acid, benzene sulfonic acid, acid halides such as benzoyl chloride, benzene sulfonyl chloride, methanesulfonyl chloride, chloroethyl formate, acid anhydrides such as benzoic anhydride, phthalic anhydride, and the like or mixtures thereof. In the event that one uses an acid halide in the above reaction, a tertiary organic base such as pyridine, dimethyl aniline, triethylamine and the like may be employed

75

as an accelerator therefor. If an acid halide is employed, one may optionally employ as an accelerator pyridine, p-toluene sulfonic acid, boro and trifluoride, and the like. Furthermore, in the event that the esterification is effected with an acid it is preferred to employ trifluoro acetic anhydride as an accelerator. Such an accelerator may be employed either in an equivalent or an excessive amount relative to the amount of the compounds represented by formula (VIII). It is to be noted, however, as discussed above, that such an accelerator need not be used.

As noted, a solvent may optionally be employed in connection with this reaction. It is not necessary, however, to do so when either or both of the acid or their reaction derivatives, or the accelerators are liquid in their normal state. It is to be noted that is preferred to employ a solvent which solvent may be chosen according to the specific properties and type of starting reactants. In this instance, it is noted that exemplary of such solvents are benzene, ether, dioxane, pyridine, and the like or mixtures thereof. It is to be noted that the compounds of formula (III) may also be prepared according to the process employed in connection with the compounds of formula (I) with the exception that the carbonyl derivative employed would have the formula:

The novel compounds of the present invention have been found to be particularly effective in the treatment of diseases of microbial origin. That is to say, that nitrone derivatives of the instant invention are particularly effective in the treatment of bacterial, fungal, and protozoal disease. The subject compounds have been found to be extremely potent and a relatively small dose thereof is sufficient for treatment. Furthermore, the toxicity of these nitrofuran derivatives is less than that of previously known derivatives of the same type. The subject compounds may be utilized in the treatment of both humans and animals either topically, orally, or by injection either when compounded as a powder, ointment, liquid, or parenteral solution with a suitable carrier therefor, and conventionally employed pharmaceutical adjuvants. It is also noted that the subject compounds may be employed in a manner similar to that of other nitrofuran derivatives in the fields of foods, agricultures, and the like wherein the removal or prevention of the growth of microbial organisms is required.

The instant invention will now be illustrated by the following more detailed examples thereof. It is to be noted, however, that the instant invention is not deemed as being limited thereto.

EXAMPLE 1

Preparation of α -[1-bromo-2-(5-nitro-2-furyl)vinyl]-N-phenyl nitrone. To a solution of 2.46 grams of α -bromo- β -(5-nitro-2-furyl)acrolein and 500 ml of ethanol, 1.42 grams of phenyl hydroxylamine and 0.2 ml of glacial acetic acid were added. The reaction was effected by stirring the mixture for a period of about 2 hours at room temperature. The resulting precipitates were collected by filtration and recrystallized from acetyl nitrile to give 1.7 grams of the subject compound as reddish orange needles which have a melting point of 159°–161° C.

EXAMPLE 2

Preparation of α -[1-bromo-2-(5-nitro-2-furyl)vinyl]-N-(2-methanesulfonyloxyethyl) nitrone.

The procedure of Example 1 was repeated with the exception that N-(2-methanesulfonyloxyethyl) hydroxyl amine was employed in lieu of phenyl hydroxyl amine. As a result, greenish yellow plates of the subject compound were formed which have a melting point of 152°–153° C.

EXAMPLE 3

Preparation of α -[1-bromo-2-(5-nitro-2-furyl)vinyl]-N-(2-acetoxyethyl) nitrone.

The procedure of Example 1 was repeated with the exception that in lieu of phenyl hydroxyl amine, N-(2-acetoxyethyl) hydroxyl amine was employed. As a result, light yellow needles of the subject compound having a melting point of 131°–133° C was formed.

EXAMPLE 4

Preparation of α -[1-bromo-2-(5-nitro-2-furyl)vinyl]-N-methyl nitrone.

4.92 grams of α -bromo- β -(5-nitro-2-furyl) acrolein was dissolved in 80 ml of ethanol at 65° C with stirring. 2.16 g of N-methylhydroxylamine hydrochloride and 2.1 g of anhydrous sodium acetate were added and the reaction mixture was kept at room temperature. The mixture was allowed to stand for 6 hours with stirring. The precipitates were collected by filtration and the filtrate was concentrated to a half volume under reduced pressure. The resulting residue, on cooling, gave additional crystals which were combined with the preceding precipitates. The crystals were recrystallized from ethanol to give 4.4 g of the intended compound as yellow, fine needles melting at 180°–181° C with decomposition.

EXAMPLE 5

Preparation of α -[2-(5-nitro-2-furyl)-1-phenylvinyl]-N-methyl nitrone.

The procedure of Example 4 was repeated with the exception that α -phenyl- β -(5-nitro-2-furyl)acrolein was employed in lieu of α -bromo- β -(5-nitro-2-furyl)acrolein. As a result, the subject compound was formed as yellow plates having a melting point at 165°–166° C with decomposition.

EXAMPLE 6

Preparation of α -[1-(2-furyl)-2-(5-nitro-2-furyl)-vinyl]-N-methyl nitrone.

The procedure of Example 4 was repeated with the exception that α -(2-furyl)- β -(5-nitro-2-furyl)acrolein was employed in lieu of α -bromo- β -(5-nitro-2-furyl)acrolein. As a result, the subject compound was formed as reddish-orange needles having a melting point of 179°–180° C with decomposition.

EXAMPLE 7

Preparation of cis- and trans- α -[2-(5-nitro-2-furyl)-1-phenylvinyl]-N-(2-hydroxyethyl) nitrones.

To a solution of 3.14 g of cis- α -phenyl- β -(5-nitro-2-furyl) acrolein in 80 ml of ethanol there was added a solution of 1.20 g of N-(2-hydroxyethyl) hydroxylamine in a 10 percent hydrochloric acid and 3.87 g of sodium acetate with stirring. The mixture was then heated at 50°–55° C. After approximately 1 hour the reaction mixture was concentrated under reduced pressure, and the residue was extracted with chloroform, washed with water and dried, followed by removal of the chloroform by distillation. The remaining crystals were recrystallized from a mixture of ethanol and hexane to give 3.13 g of the intended compound of the cis-type as yellow plates melting at 114°–116° C.

The mother liquor was concentrated to dryness and the residue was recrystallized from chloroform to give 0.15 g of the intended compound of the trans-type as yellow needles melting at 162°–164° C.

EXAMPLE 8

Preparation of α -[1-bromo-2-(5-nitro-2-furyl)vinyl]-N-(2-hydroxyethyl) nitrone.

The procedure of Example 7 was repeated with the exception that α -bromo- β -(5-nitro-2-furyl) acrolein was employed in lieu of cis- α -phenyl- β -(5-nitro-2-furyl) acrolein. As a result, the subject compound was obtained which had a melting point of 160°–162° C.

EXAMPLE 9

Preparation of cis- and trans- α -[1-(2-furyl)-2-(5-nitro-2-furyl)vinyl]-N-(2-hydroxyethyl) nitrone.

The procedure of Example 1 was repeated with the exception that cis- and trans- α -(2-furyl)- β -(5-nitro-2-furyl) acroleins were employed in lieu of cis- α -phenyl- β -(5-nitro-2-furyl) acrolein. As a result, the cis- and trans- form of the subject compound were formed as orange needles having a melting point of 169° - 170° C with decomposition and 120° - 122° C with decomposition, respectively.

EXAMPLE 10

Preparation of α -[1-bromo-2-(5-nitro-2-furyl)vinyl]-N-(2-hydroxypropyl) nitrone.

The procedure of Example 8 was repeated with the exception that N-(2-hydroxypropyl)hydroxylamine was employed in lieu of N-(2-hydroxyethyl) hydroxylamine. As a result, greenish-yellow needles of the subject compound were prepared having a melting point of 124° - 126° C.

EXAMPLE 11

Preparation of α -[1-bromo-2-(5-nitro-2-furyl)vinyl]-N-(1-methyl-2-hydroxyethyl) nitrone.

The procedure of Example 8 was repeated with the exception that N-(1-methyl-2-hydroxyethyl) hydroxylamine was employed in lieu of N-(2-hydroxyethyl) hydroxylamine. As a result, yellow needles of the subject compound having a melting point of 191° - 193° C was formed.

EXAMPLE 12

Preparation of α -[1-bromo-2-(5-nitro-2-furyl)-vinyl]-N-(2-furyl) nitrone.

The procedure of Example 8 was repeated with the exception that N-(2-furyl)hydroxylamine was employed in lieu of N-(2-hydroxyethyl)hydroxylamine. As a result, greenish-yellow needles of the subject compound having a melting point of 158° - 159° C was produced.

EXAMPLE 13

Production of α -[2-(5-nitro-2-furyl)-1-phenylvinyl]-N-(1-methyl-2-hydroxyethyl)nitro.

The procedure of Example 11 was repeated with the exception that α -phenyl- β -(5-nitro-2-furyl) acrolein was employed in lieu of a α -bromo- β -(5-nitro-2-furyl) acrolein. As a result, yellow needles of the subject compound having a melting point of 152° - 154° C were produced.

EXAMPLE 14

Preparation of α -[2-(5-nitro-2-furyl)-1-phenylvinyl]-N-(2-hydroxypropyl) nitrone.

The procedure of Example 13 was repeated with the exception that N-(2-hydroxypropyl) hydroxylamine was employed in lieu of N-(1-methyl-2-hydroxyethyl) hydroxylamine. As a result, yellow needles of the subject compound having a melting point of 156° - 157° C was formed.

EXAMPLE 15

Preparation of α -[1-bromo-2-(5-nitro-2-furyl)vinyl]-N-(1,3-di-hydroxy-2-propyl) nitrone.

The procedure of Example 12 was repeated with the exception that N-(1,3-di-hydroxypropyl) hydroxylamine was employed in lieu of N-(2-furyl) hydroxylamine. As a result, greenish-yellow needles of the subject compound having a melting point of 186° - 187° C was produced.

EXAMPLE 16

Preparation of cis- and trans- α -[2-(5-nitro-2-furyl)-1-phenylvinyl]-N-(2-furyl) nitrone.

The procedure of Example 12 was repeated with the exception that cis- and trans- α -phenyl- β -(5-nitro-2-furyl) acroleins were employed in lieu of α -bromo- β -(5-nitro-2-furyl) acroleins. As a result, the cis- form of the subject compound as orange plates having a melting point of 138° - 140° C was produced. The trans- type as yellowish-orange needles having a melting point at 168° - 169° C was produced.

EXAMPLE 17

Preparation of cis- and trans- α -[1-(2-furyl)-2-(5-nitro-2-furyl)vinyl]-N-(2-hydroxypropyl) nitrone.

The procedure of Example 16 was repeated with the exception that cis- and trans- α -(2-furyl)- β -(5-nitro-2-furyl) acroleins were employed in lieu of cis- and trans- α -phenyl- β -(5-nitro-2-furyl) acroleins. As a result, needles melting at 157° - 158° C (cis-type) and 140° - 141° C (trans-type) were produced.

EXAMPLE 18

Preparation of α -[1-bromo-2-(3-nitro-2-furyl)vinyl]-N-2-methanesulfonyl-oxyethyl) nitrone.

To a solution of 1.0 g of α -[1-bromo-2-(5-nitro-2-furyl)vinyl]-N-(2-hydroxyethyl) nitrone in 8 ml of anhydrous pyridine there was added under cooling 0.5 g of methanesulfonyl chloride. The reaction mixture was allowed to stand with stirring at room temperature for 1 hour. Water was then added to the reaction mixture and the precipitating yellow crude crystals were collected by filtration, washed with water and recrystallized from ethanol to give 1.02 g of the intended compound as greenish-yellow plates melting at 152° - 153° C.

EXAMPLE 19

Preparation of α -[1-bromo-2-(5-nitro-2-furyl)vinyl]-N-(2-acetoxyethyl) nitron.

To a solution of 1.0 g of α -[1-bromo-2-(5-nitro-2-furyl)vinyl]-N-(2-hydroxyethyl) nitrone in 8 ml of anhydrous pyridine there was added with cooling 1 ml of acetic anhydride. The reaction was effected with stirring at room temperature for a period of about 2 hours. Water was added to the reaction mixture and the stirring was conducted for 30 minutes to decompose any excess acetic anhydride. The precipitating crystals were then collected by filtration and washed with water. The resulting crude crystals were recrystallized from ethanol to give 1.5 g of the intended compound as yellowish orange needles melting at 131° - 133° C.

EXAMPLE 20

Preparation of α -[2-(5-nitro-2-furyl) vinyl]- α -phenyl-N-methyl nitro.

To a solution of 2.43 g of 5-nitro-2-furfurylidene acetophenone in 20 ml of dioxane warmed at 50° C there was added 0.61 g of methylhydroxylamine and 0.1 ml of glacial acetic acid. The mixture was kept at 50° C with stirring and then allowed to stand over-night at room temperature. The starting ketone which precipitated on standing was removed by filtration and the filtrate was concentrated under reduced pressure. The residue was subjected to silicagel chromatography to afford crude crystals therefrom. The resulting crude crystals were recrystallized repeatedly from methanol to give 0.61 g of the intended compound as fine, orange needles melting at 194° - 196° C.

EXAMPLE 21

Preparation of α -[2-(5-nitro-2-furyl) vinyl]- α -phenyl-N-(1-hydroxy-2-propyl) nitro.

To a solution of 2.43 g of 5-nitro-2-furfurylidene acetophenone in 50 ml of ethanol warmed at 50° - 60° C., there was added 1.65 g of 1-hydroxy-2-propylhydroxylamine. The reaction was carried out at room temperature with stirring for 2 days. The reaction mixture was cooled and the precipitating crystals (starting ketone) were removed by filtra-

tion. The filtrate was concentrated under reduced pressure, and the residue was subjected to silica-gel chromatography to yield the crude product. The resulting crude crystals were recrystallized from a mixture of n-hexane and acetone to give 0.59 g of the intended compound as orange needles melting at 178° - 180° C.

EXAMPLE 22

Preparation of α -[2-(5-nitro-2-furyl) vinyl]-N-(2-benzyloxyethyl) nitrone.

To a solution of 0.2 g of α -[2-(5-nitro-2-furyl) vinyl]-N-(2-hydroxyethyl) nitrone in 2 ml of anhydrous pyridine there was added 0.15 ml of benzoyl chloride with ice-cooling and stirring. After the reaction had progressed for about 3 hours under the same conditions, the reaction mixture was poured into ice water, and the precipitating crude crystals were collected by filtration and recrystallized from dilute ethanol to give 0.3 g of the intended compound as faintly orange needles melting at 126° - 128° C.

EXAMPLE 23

Preparation of α -(5-nitro-2-furyl)-N-(2-benzyloxyethyl) nitrone.

The procedure of Example 22 was repeated with the exception that α -(5-nitro-2-furyl)-N-(2-hydroxyethyl) nitrone was employed in lieu of α -[2-(5-nitro-2-furyl) vinyl]-N-(2-hydroxyethyl) nitrone. The greenish-yellow needles of the subject compound were found to have a melting point of 141° - 143° C.

EXAMPLE 24

Preparation of α -methyl- α -[2-(5-nitro-2-furyl) vinyl]-N-(2-benzyloxyethyl) nitrone.

The procedure of Example 23 was repeated with the exception that α -methyl- α -[2-(5-nitro-2-furyl) vinyl]-N-(2-hydroxyethyl) nitrone was employed in lieu of α -(5-nitro-2-furyl)-N-(2-hydroxyethyl) nitrone. As a result, orange prisms of the subject compound having a melting point of 143° - 144° C were produced.

EXAMPLE 25

Preparation of α -(5-nitro-2-furyl)-N-(2-ethoxycarbonyl-oxethyl) nitrone.

To a solution of 0.8 g of α -(5-nitro-2-furyl)-N-(2-hydroxyethyl) nitrone in 8 ml of anhydrous pyridine there was added under ice-cooling and stirring 0.46 ml of chloroethyl formate, and the reaction was effected at room temperature for 9 hours. The reaction mixture was then poured into ice water and extracted with chloroform. The extracts were washed with water, dried with magnesium sulfate and concentrated under reduced pressure. To this residue ethanol was added and the separated crude crystals were collected by filtration and recrystallized from ethanol to give 1.13 g of the intended product as yellowish orange plates melting at 88° - 89° C.

EXAMPLE 26

Preparation of α -(5-nitro-2-furyl)-N-[2-(β -carboxypropionyloxy) ethyl] nitrone.

To a solution of 0.5 g of α -(5-nitro-2-furyl)-N-(2-hydroxyethyl) nitrone in 3 ml of anhydrous pyridine there was added 300 mg of succinic anhydride, and the reaction was carried out at room temperature for 3 hours and at 95° C for an additional 2 hours under stirring. The reaction mixture was concentrated under reduced pressure, and the precipitating crystals were collected by filtration and recrystallized from ethanol to give 0.8 g of the intended product as yellowish scales melting at 137° - 139° C.

EXAMPLE 27

Preparation of α -(5-nitro-2-furyl)-N-[2-(2-carboxybenzoyloxy)ethyl] nitrone.

The procedure of Example 26 was repeated with the exception that phthalic anhydride was employed in lieu of succinic anhydride. As a result, yellow needles of the subject compound having a melting point of 101° - 102° C was produced.

EXAMPLE 28

Preparation of α -(5-nitro-2-furyl)-N-[2-(p-toluenesulfonyloxy)ethyl] nitrone.

10 To a solution of 0.5 g of α -(5-nitro-2-furyl)-N-(2-hydroxyethyl) nitrone in 4 ml of anhydrous pyridine there was added under stirring 500 mg of p-toluenesulfonyl chloride, and the reaction was carried out at room temperature under stirring for 5 hours. The reaction mixture was then poured into ice water, and the precipitating crude crystals were collected by filtration and recrystallized from a mixture of water and dimethyl formamide to give 0.52 g of the intended product as greenish-yellow prisms melting at 189° - 190° C.

20

EXAMPLE 29

Preparation of α -(5-nitro-2-furyl)-N-(1,3-bis-methane-sulfonyloxy-2-propyl) nitrone.

25 To a solution of 0.46 g of α -(5-nitro-2-furyl)-N-(1,3-dihydroxy-2-propyl) nitrone in 2 ml of anhydrous pyridine there was added under ice-cooling and stirring 570 mg of methanesulfonyl chloride, and the reaction was effected at room temperature for 1 hour. The reaction mixture was poured into water, and the precipitating crude crystals were collected and recrystallized from ethanol to give 0.7 g of the intended compound as greenish-yellow needles melting at 160° - 161° C.

30

EXAMPLE 30

35 Preparation of α -(5-nitro-2-furyl)-N-(2-methanesulfonyloxyethyl) nitrone.

The procedure of Example 25 was repeated with the exception that methanesulfonyl chloride was employed in lieu of p-toluenesulfonyl chloride. As a result, greenish-yellow plates of the subject compound having a melting point of 151° - 152° C were produced.

What is claimed is:

1. A Nitrone derivative represented by the formula

wherein m is an integer of 0 to 1; R_1 represents a member selected from the group consisting of hydrogen, halogen, furyl and phenyl; R_2 represents a member selected from the group consisting of hydrogen, alkyl having from 1 to 4 carbon atoms and phenyl; R_3 represents a member of the group consisting of phenyl and $A - (X)_n$, only when R_1 represents a member selected from the group consisting of halogen, furyl and phenyl, R_2 represents hydrogen and m is 1; $A - (Y)_n$, only when R_1 represents hydrogen and R_2 represents a member selected from the group consisting of hydrogen and alkyl having from one to four carbon atoms; and $A - (Z)_n$, only when R_1 represents hydrogen, R_2 represents phenyl and m is an integer of 1; in which A represents alkyl having from one to six carbon atoms; X represents a member selected from the group consisting of hydrogen, hydroxyl, furyl, alkylsulfonyloxy having an alkyl group of one to four carbon atoms and alkanoyl having an alkyl group of from one to three carbon atoms; Y represents a member selected from the group consisting of benzenesulfonyloxy, toluenesulfonyloxy, alkylsulfonyloxy having from one to four carbon atoms, benzoyloxy, salicyloyloxy, carboxy benzoyloxy and alkoxy carbonyloxy having an alkyl group of from one to four carbon atoms and carboxy alkanoyloxy having from three to six carbon atoms, Z represents a member selected from the group consisting of hydrogen and hydroxy, and n is an integer of from 1 to 3.

70

75

2. The compound of claim 1 wherein R_1 represents a member selected from the group consisting of halogen, furyl and phenyl, R_2 represents hydrogen and m is 1.
3. The compound of claim 1 wherein R_1 represents hydrogen and R_2 represents a member selected from the group consisting of hydrogen and an alkyl having from about one to about four carbon atoms.

4. The compound of claim 1 wherein R_1 represents hydrogen, R_2 represents phenyl and m is 1.

5. The nitrone derivative of claim 1 wherein said derivative is α -[1-bromo-2-(5-nitro-2-furyl)vinyl]-N-methyl nitrone.

6. The nitrone derivative of claim 1 wherein said derivative is α -[1-bromo-2-(5-nitro-2-furyl)vinyl]-N-(2-hydroxypropyl)nitrone.

7. The nitrone derivative of claim 1 wherein said derivative is α -[1-bromo-2-(5-nitro-2-furyl)vinyl]-N-(1-methyl-2-hydroxyethyl)nitrone.

8. The nitrone derivative of claim 1 wherein said derivative is α -[1-bromo-2-(5-nitro-2-furyl)vinyl]-N-(1,3-dihydroxy-2-propyl)nitrone.

9. The nitrone derivative of claim 1 wherein said derivative is α -[1-bromo-2-(5-nitro-2-furyl)vinyl]-N-(2-hydroxyethyl)nitrone.

10. The nitrone derivative of claim 1 wherein said derivative is α -[1-bromo-2-(5-nitro-2-furyl)vinyl]-N-(2-furyl)nitrone.

11. The nitrone derivative of claim 1 wherein said derivative is α -[1-bromo-2-(5-nitro-2-furyl)vinyl]-N-phenyl nitrone.

12. The nitrone derivative of claim 1 wherein said derivative is α -[1-bromo-2-(5-nitro-2-furyl)vinyl]-N-(2-methanesulfonyloxyethyl)nitrone.

13. The nitrone derivative of claim 1 wherein said derivative is α -[1-bromo-2-(5-nitro-2-furyl)vinyl]-N-(2-acetyloxyethyl)nitrone.

14. The nitrone derivative of claim 1 wherein said derivative is α -[2-(5-nitro-2-furyl)-1-phenylvinyl]-N-(1-methyl-2-hydroxyethyl)nitrone.

15. The nitrone derivative of claim 1 wherein said derivative is α -[2-(5-nitro-2-furyl)-1-phenylvinyl]-N-(2-hydroxypropyl)nitrone.

16. The nitrone derivative of claim 1 wherein said derivative is α -[2-(5-nitro-2-furyl)-1-phenylvinyl]-N-methyl nitrone.

17. The nitrone derivative of claim 1 wherein said derivative is α -[2-(5-nitro-2-furyl)-1-phenylvinyl]-N-(2-hydroxyethyl)nitrone.

18. The nitrone derivative of claim 1 wherein said derivative is α -[2-(5-nitro-2-furyl)-1-phenylvinyl]-N-(2-furyl)nitrone.

19. The nitrone derivative of claim 1 wherein said derivative is α -[2-(5-nitro-2-furyl)vinyl]- α -phenyl-N-methyl nitrone.

20. The nitrone derivative of claim 1 wherein said derivative is α -[2-(5-nitro-2-furyl)vinyl]- α -phenyl-N-(1-hydroxy-2-propyl)nitrone.

21. The nitrone derivative of claim 1 wherein said derivative is α -[2-(5-nitro-2-furyl)vinyl]-N-(2-benzoyloxyethyl) nitrone.

22. The nitrone derivative of claim 1 wherein said derivative is α -(5-nitro-2-furyl)-N-(2-benzoyloxyethyl)nitrone.

23. The nitrone derivative of claim 1 wherein said derivative is α -(5-nitro-2-furyl)-N-(2-methanesulfonyloxyethyl) nitrone.

24. The nitrone derivative of claim 1 wherein said derivative is α -(5-nitro-2-furyl)-N-(2-tosyloxyethyl)nitrone.

25. The nitrone derivative of claim 1 wherein said derivative is α -(5-nitro-2-furyl)-N-(1,3-bismethanesulfonyloxy-2-propyl)nitrone.

26. The nitrone derivative of claim 1 wherein said derivative is α -[2-(5-nitro-2-furyl)vinyl]-N-(2-ethoxycarbonyl-oxethyl)nitrone.

27. The nitrone derivative of claim 1 wherein said derivative is α -(5-nitro-2-furyl)-N-[2-(2-carboxybenzoyloxy)ethyl]nitrone.

28. The nitrone derivative of claim 1 wherein said derivative is α -(5-nitro-2-furyl)-N-[2-(β -carboxypropionyloxy)ethyl]nitrone.

29. The nitrone derivative of claim 1 wherein said derivative is α -methyl- α -[2-(5-nitro-2-furyl)vinyl]-N-(2-benzoyl-oxethyl)nitrone.

30. The nitrone derivative of claim 1 wherein said derivative is α -[1-(2-furyl)-2-(5-nitro-2-furyl)vinyl]-N-methyl nitrone.

31. The nitrone derivative of claim 1 wherein said derivative is α -[1-(2-furyl)-2-(5-nitro-2-furyl)vinyl]-N-(2-hydroxyethyl)nitrone.

32. The nitrone derivative of claim 1 wherein said derivative is α -[1-(2-furyl)-2-(5-nitro-2-furyl)vinyl]-N-(2-furyl)nitrone.

UNITED STATES PATENT OFFICE
CERTIFICATE OF CORRECTION

Patent No. 3,666,754 Dated May 30, 1970

Inventor(s) MINAMI ET AL

It is certified that error appears in the above-identified patent and that said Letters Patent are hereby corrected as shown below:

Delete issuance date of "May 30, 1970" and insert
"May 30, 1972."

Signed and sealed this 9th day of January 1973.

(SEAL)
